UNITED STATES PATENT OFFICE.

FREDERICK TURNER, OF PHILADELPHIA, PENNSYLVANIA.

DESIGN FOR A BUTTON.

SPECIFICATION forming part of Design No. 16,666, dated April 27, 1886.

Application filed March 3, 1886. Serial No. 193,910. Term of patent 14 years.

To all whom it may concern:

Be it known that I, FREDERICK TURNER, a citizen of the United States, residing at Philadelphia, in the county of Philadelphia and State of Pennsylvania, have invented and produced a new and original Design for Buttons, of which the following is a specification, reference being had to the accompanying drawings, forming part thereof.

10 Figure 1 is a face view of a button bearing my design, and Fig. 2 is an edge view of the same.

My design consists of a pentagon, a sphere, a triangle, and a spear or lance.

15 I have illustrated my design by having the face of the button pentagonal in outline and inclosing a raised sphere, which latter is pro-

vided with latitudinal lines. Upon the sphere is centrally represented a triangle, and from the base to the apex of the pentagon through the sphere and triangle is placed a spear or lance.

What I claim, and desire to secure by Letters Patent, is—

The design for a button, substantially as herein shown and described, consisting of a pentagon inclosing a sphere, a triangle, and a spear or lance.

In testimony whereof I affix my signature in presence of two witnesses.

FREDERICK TURNER.
